By *James O. Sherry*
his Atty.

UNITED STATES PATENT OFFICE.

VALERIUS T. JENNINGS, OF CHICAGO, ILLINOIS.

HANGER BAR FOR OUTLET BOXES.

Application filed August 22, 1925. Serial No. 51,756.

This invention relates to hangers for outlet boxes and articles of similar nature, and among its objects are economy in the production thereof, simplicity, ease of assembly, strength and durability. With these and other objects in view, this invention consists of a hanger for outlet boxes and the like, having a channel shaped hanger bar made of light weight material, upon which the box is adjustably secured by a metal yoke member that extends across the bar and is secured to the box by screws or otherwise. It further consists in a hanger having a carrier head or fixture stud formed with a shouldered part that rests upon the top of the box and enters the channel of the hanger bar, whereby the carrier head or fixture stud is supported and held against rotation in the box. The invention further consists in the several novel features hereinafter fully set forth and claimed. The invention is clearly illustrated in the accompanying drawing, in which:

Fig. 1 is a plan of a hanger for outlet boxes embodying a simple form of the present invention; Fig. 2 is a view looking at the underside of the device; Fig. 3 is a detail, central, longitudinal section of the device taken on the line 3—3 of Fig. 1; Fig. 4 is a detail cross section of the device, taken on the line 4—4 of Fig. 1; and Fig. 5 is a perspective view of the carrier head or fixture stud detached from the remainder of the device.

Referring to said drawing, which illustrates one embodiment of the invention applied to a ceiling outlet box, the reference character 10 designates the hanger bar of the device, which in accordance with the present form of the invention is channel shaped and preferably formed from a light gauge metal strip bent up or otherwise shaped up into a channel shape. The hanger bar is usually made of a length sufficient to extend between two adjacent joists of a floor and is provided with nail or screw holes 11, adjacent its ends, through which nails or screws may be inserted, whereby it may be readily secured to and supported by floor joists or any other suitable supports.

The outlet box 12 is of the usual and well known type, having a top portion 13, formed with a marginal down turned flange 14, and with the usual "knockout" places 15,

which may be forced open to form the openings for the pipes or armored casings in which the conductor cords are usually contained. A centrally located hole 16 is formed in the top portion 13, and adjacent said hole, on diametrically opposite sides thereof, screw holes 17 are formed, for the reception of clamping screws, as will appear later. Extending through the hole 16 is the carrier head or fixture stud 18, which is of novel form. Said carrier head is formed with a threaded stem portion 19, to which an electric light fixture may be attached in the usual manner, and, in accordance with the present embodiment of the invention, above the threaded stem portion, the diameter of the carrier head is increased slightly, forming a head portion 20, which enables it to fairly fit in the hole 16, which as a preference is of the same diameter as the holes formed at the "knockout" places 15. The part 20 above the threaded stem portion 19, is formed on its upper side with an elongated lug 21, the ends 22 of which project beyond the opposite sides of the head part 20 and rest upon the top portion 13 of the outlet box and support the carrier head or fixture stud thereon. The channeled hanger bar 10 is preferably made narrower than the carrier head, and the width of the lug 21 may be made to correspond with the width of the channel of said hanger bar and the height of the lug 21, above the top of the head part 20, is practically the same as the height of the channel, whereby the lug may be wholly contained in said channel. The stem 19 of the carrier head is inserted downwards through the hole 16 in assembling the parts, and when the projecting end portions 22 of the lug 21, rest upon the top portion 13 of the outlet box, the top faces 23 of the head part 20 are then substantially flush with the top face of the outlet box. The shape of the carrier head is one that enables the carrier head to be easily and cheaply made on a screw machine, or other suitable automatic machine.

Extending across the hanger bar and carrier head is a yoke member 24, preferably struck up from a metal strip of suitable dimensions to form the central offset part 25, which extends over and down along the side edges of the hanger bar 10. Beyond the offset portion 25 are end portions 26, which

are drilled and tapped at places coinciding with the screw holes 17, for the reception of screws 27.

In the assembled hanger, the carrier head 18, extends through the central hole 16 in the outlet box 12 and the projecting end portions 22 of its lug 21 rest upon the top face of the box. The hanger bar 10 extends diametrically over the top face of the outlet box and the lower edges of its flanges engage therewith. The lug 21 of the carrier head 18 is contained in the channel of the hanger bar 10, and is kept from turning therein, by reason of the engagement of the sides of the lug with the contiguous inner sides of the flanges of the hanger bar. The yoke member 24 extends across the hanger bar 10 and when the screws 27 have been screwed up tight the offset part 25 of the yoke member is clamped tightly upon the hanger bar, thereby clamping it down tightly against the top face of the outlet box.

The parts are easily assembled by inserting the stem of the carrier head through the central hole in the top portion of the outlet box, placing the yoke member thereover, and inserting the screws through the screw holes in the outlet box and yoke member. The hanger bar may now be slipped between the lug of the carrier head and offset portion 25 of the yoke member, and the outlet box adjusted to any desired position thereon, after which the screws 27 may be tightened up thereby securely clamping the parts together.

While the invention has been shown and described in connection with a ceiling outlet box, it is to be understood that it is applicable to other forms and types of outlet boxes and articles of similar nature, and that the term "outlet box" wherever used in the specifications or claims is intended to include all analogous articles.

More or less variation of the exact details of construction is possible without departing from the spirit of this invention; I desire, therefore, not to limit myself to the

exact form of the construction shown and described, but intend, in the following claims, to point out all of the invention disclosed herein.

I claim as new, and desire to secure by Letters Patent:

1. A hanger for outlet boxes, comprising in combination, a channel shaped hanger bar, an outlet box having a top portion flat in its entirety and having a hole in its flat top portion, a single piece carrier head extending through said hole and having a threaded stem portion there below and a narrow, elongated, laterally projecting, bar engaging lug located above the flat top portion of the outlet box and adapted to rest thereon and to enter the channel of the hanger bar, whereby the carrier head is directly supported on and held against rotation relative to said outlet box, a removable and replaceable yoke member extending across said hanger bar, and means between said outlet box and yoke member for clamping the yoke member down upon the hanger bar and therewith clamping the hanger bar down upon the outlet box.

2. A hanger for outlet boxes, comprising in combination, a channel shaped hanger bar, an outlet box having a top portion flat in its entirety and having a centrally located hole in its flat top portion, a carrier head comprising a threaded stem portion adapted for engagement with a light fixture, a head portion above said stem portion of greater diameter than the stem portion and adapted to engage in said hole in the top portion of the outlet box and a narrow lug on said head portion having projecting end portions adapted to bear against said top portion of the outlet box and enter the channel of said channel shaped hanger bar and a yoke member arranged to be secured to the top portion of said outlet box with the hanger bar clamped between said top portion of the outlet box and yoke member.

VALERIUS T. JENNINGS.
